UNITED STATES PATENT OFFICE.

GLEN R. SISSON, OF PENDLETON, INDIANA.

AUTOMATIC CHOKER FOR CARBURETORS.

Application filed April 25, 1923. Serial No. 634,576.

To all whom it may concern:

Be it known that I, GLEN R. SISSON, a citizen of the United States, residing at Pendleton, in the county of Madison and State of Indiana, have invented new and useful Automatic Chokers for Carburetors, of which the following is a specification.

It is the object of my invention to provide an automatic choker for carburetors,

10 for regulating the air-supply, especially during starting, so that an efficient mixture under both starting and operating conditions may be obtained without requiring special skill on the part of the operator.

15 In the operation of automobiles, many drivers have difficulty, especially in and just after starting, in getting the right amount of air. They may fail to start by having too much air. They may fail to start by having 20 too little air. They are apt to have inefficient operation after starting by reason of too little air, on account of keeping the choker closed too long; although many operators kill their engine immediately after starting 25 by opening the choker valve too wide before the engine is heated up, thus permitting too large an air supply for a cold engine.

In accordance with my invention, I control a supply of air by the operation of the 30 starter motor, so that while the starter motor is in operation this supply of air will be largely or wholly shut off. I preferably arrange this air-supply which is thus controlled by the operation of the starting 35 motor so that it is one of two supplies, leading to the carburetor in parallel; and preferably control the second air-supply by a thermostatic device, responsive as shown to the temperature of the engine in some 40 suitable way, so that such second air-supply is opened more widely as the temperature of the engine rises. My invention contemplates various combinations of less than all these features, as the claims set forth.

45 The accompanying drawing illustrates my invention: Fig. 1 is a side elevation of an automobile engine equipped with my invention, the structure being shown semi-diagrammatically; and Fig. 2 is an enlarged 50 elevation of the controlling means for the air-supply.

The engine 10 is supplied with explosive mixture by the usual carburetor 11, which supplies such explosive mixture to the engine 55 through any convenient intake manifold 12; and the exhaust gases from the engine are

discharged through an exhaust manifold 13 in the usual way. At least part of the air intake for the carburetor 11 is conveniently derived from the usual stove 15 on the exhaust manifold 13, so that the air will be heated by the heat of the exhaust gases, though this stove is not essential to my invention.

The air-supply pipe 16 for the carburetor 65 11 has two branches 17 and 18, both of which join into the pipe 16 and communicate therethrough with the carburetor 11. These two branches are both shown as deriving their air from the stove 15, though 70 that is not essential. I have shown the two pipes 17 and 18 merely diagrammatically, without intending to indicate any definite relation as to their relative sizes. The relation between these two pipes may be varied 75 as desired.

In the branch-pipe 17 is a choker valve 20, which is normally spring-pressed to the open position shown but is arranged to be closed when the circuit of the starter motor 21 is 80 closed. The starter motor 21 is supplied with current from the usual battery 22; and is controlled by the usual foot-switch 23, which when depressed closes the circuit of such starter motor. The controlling device 85 for the choker valve 20 is shown as a solenoid 24 connected in shunt to the starter motor 21, so that it is controlled in common with such starter motor by the foot-switch 23; which solenoid 24 has a core 25 suitably 90 connected to an operating arm 26 of the choker valve 20. A spring 27 or other returning device holds the choker valve 20 normally in open position, but when the solenoid 24 is energized the choker valve 20 95 is moved to closed position to shut off the supply of air to the carburetor through the branch pipe 17.

Thus when the foot-switch 23 is closed to complete the circuit for the starter motor 100 21, and such starter motor is operating to turn over the engine 10, the air-supply through the branch pipe 17 is shut off, and the supply pipe 16 of the carburetor must derive its whole supply of air from the branch pipe 18. This cuts down the quantity 105 of air delivered to the carburetor, and thus assists in starting. As soon as the foot-switch 23 is released and allowed to open, both the starter motor 21 and the solenoid 24 110 are de-energized, and the choker valve 20 is opened by its spring 27, thus admitting

more air to the carburetor after the engine is started.

While the branch-pipe 18 may be valveless, I prefer to provide it also with a 5 choker valve 30. This choker valve 30 is opened and closed as the temperature of the engine rises and falls respectively. To this end, the operating arm 31 of the choker valve 30 is connected to any suitable thermostat 32, suitably arranged to be responsive to the temperature of the engine itself, or of something which varies in temperature with the engine. The thermostat 32 is shown as a single two-metal thermostat 10 strip, supported at one end on the exhaust manifold 13, and connected at the other or free end by a link 33 to the arm 31. The free end of the thermostat 32 bows upward upon increase of temperature, and downward upon decrease of temperature, if the parts are arranged as shown, but this is of course inessential.

Therefore, when the engine is started cold, both choker valves 20 and 30 are closed, and 25 very little air is supplied to the carburetor. As soon as the engine starts, the choker valve 20 is opened, to admit more air; and as the engine warms up, the choker valve 30 is gradually opened, to admit more air in proportion 30 to the heating up of the engine. If when the engine is started it is not cold, the choker valve 30 is correspondingly open, to admit air in accordance with the temperature of the engine; and the starting choking 35 is only by the choker valve 20, which is opened as soon as the driver releases the foot-switch 23.

This makes a substantially fool-proof arrangement, requiring no skill or care on the 40 part of the operator to get suitable mixtures for starting under all conditions, and for running under different temperature conditions.

I claim as my invention:

45 1. A choking device for the carburetor of an internal combustion engine having a starting device, comprising means for automatically choking the supply of air to the carburetor during the starting of the engine by said starting device, and means for varying the choking of the supply of air to the carburetor in accordance with the temperature of the engine.

55 2. A choking device for an internal combustion engine having a carburetor and a starting device, comprising means for automatically choking the supply of air to the carburetor during the starting of the engine by said starting device, and additional means for choking the supply of air to said carburetor in accordance with the temperature of the engine.

60 3. In combination, an internal combustion engine, a carburetor and a starting device therefor, said carburetor being provided

with a branched air-inlet, and a choker valve arranged in one of said branches and arranged to normally open it but to close it automatically during the operation of said starting device.

70 4. In combination, an internal combustion engine, a carburetor and a starting device therefor, said carburetor being provided with a branched air-inlet, and a choker valve arranged in one of said branches and controlled jointly with said starting device.

75 5. In combination, an internal combustion engine, a carburetor and a starting device therefor, said carburetor being provided with a branched air-inlet, a choker valve arranged in one of said branches and controlled jointly with said starting device, and a choker valve arranged in the other of said branches and controlled by the temperature of the engine.

80 6. In combination, an internal combustion engine, a carburetor therefor, said carburetor being provided with a branched air-inlet, a choker valve arranged in one of said branches, and means for controlling said choker valve by the temperature of the engine, the other branch being free from control by the temperature of the engine.

85 7. A choking device for the carburetor of an internal combustion engine having a starting device, comprising means controlled jointly with said starting device for automatically choking the supply of air to the carburetor during the starting of the engine by said starting device, and a thermostat for varying such choking.

90 8. The combination set forth in claim 7, with the addition that said thermostat is responsive to the temperature of the engine.

95 9. A choking device for the carburetor of an internal combustion engine having a starting device, comprising means controlled jointly with said starting device for automatically choking the supply of air to the carburetor during the starting of the engine by said starting device, and means for decreasing the choking produced by said choker valve upon increase in temperature of the engine.

100 10. A choking device for the carburetor of an internal combustion engine having a starting device, comprising means controlled jointly with said starting device for automatically choking the supply of air to the carburetor during the starting of the engine by said starting device, said choking means being arranged to increase the air supply upon cessation of the starting-device operation, and a thermostat for varying the proportionate extent to which such air supply is so increased.

11. A choking device for the carburetor of an internal combustion engine having a starting device, comprising means controlled jointly with said starting device for auto-

matically choking the supply of air to the carburetor during the starting of the engine by said starting device, and a thermostat also exerting a control on the choking of said air supply.

12. The combination set forth in claim 11, with the addition that said thermostat is responsive to the temperature of the engine.

13. The combination set forth in claim 11,

with the addition that the air-supply to the carburetor is branched, and said first-named means and said thermostat exert their choking actions in different branches of said air-supply.

In witness whereof, I have hereunto set my hand at Indianapolis, Indiana, this 23d day of April, A. D. one thousand nine hundred and twenty-three.

GLEN R. SISSON.
